UNITED STATES PATENT OFFICE.

EDWARD RUANE, OF RUTLAND, VERMONT, ASSIGNOR OF ONE-HALF HIS
RIGHT TO JOHN N. BAXTER, OF SAME PLACE.

IMPROVEMENT IN RAILROAD-RAIL CHAIRS.

Specification forming part of Letters Patent No. 173,180, dated February 8, 1876; application filed
January 17, 1876.

To all whom it may concern:

Be it known that I, EDWARD RUANE, of Rutland, in the county of Rutland and State of Vermont, have invented a new and useful Improvement in Chairs for Railroad-Rails; and I do hereby declare that the following is a full, clear, and exact description of the same, reference being had to the accompanying drawings, forming part of this specification, in which—

Figure 1 is a longitudinal section of my improved rail-chair applied under the joint of two sections of a rail. Fig. 2 is a perspective view of the chair with one section of a rail seated in it. Fig. 3 is a cross-section of the rail and chair in the line *x x*, Fig. 1. Fig. 4 is a cross-section of the rail and of a slightly-modified form of chair in the line *y y* of Fig. 1.

My invention relates to a rail-chair for the joints of railroad-rails; and the nature of the same consists, first, in two flanged plates of a form corresponding, respectively, to the sides of the rails, and hinged together by one of their ends beneath the rail, so as to open and close horizontally; second, in the combination, with these plates or jaws thus hinged together, of a base-plate, and vertical spikes, and a horizontal bolt which passes under the rail.

By this construction the meeting-ends of two rails can be placed with their ends together upon the base-plate and hinged ends of the side plates, and then the free ends of the side plates can be swung in horizontally against the sides of the rail just above the base-plate, and tied together by a horizontal bolt passed beneath the rail from side to side without perforating the rail, and fastened firmly to the ties by vertical spikes; and in case it is desired to take up the rail-sections the plates of the chair can be spread apart laterally by simply withdrawing the single horizontal bolt and vertical spikes, and the rail removed without disturbing the chair.

To enable others skilled in the art to make and use my invention, I will proceed to de-

scribe the same with references to the drawings.

A A represent the sections of a railroad-rail; B B, the side jaws or plates of the chair; C C, horizontal, or nearly so, hinging flanges, formed on these plates at one of their ends; and D D, vertical flanges or lugs, formed on these plates at their other ends. E is a base-plate, which rests on the railroad-tie G, and underneath the joint between the ends of the rail-sections. This plate is broad enough to extend beyond the rail and jaws or plates, as shown in Figs. 2 and 4. H is a pivot for fastening the flanges C C together, and thereby forming a horizontal hinge-joint between the plates B B beneath the rail, as shown in Figs. 1, 2, and 3. I is a horizontal bolt passed through the flanges D D of the plates and beneath the rail, as shown in Fig. 1. This bolt has a hooked head, and a screw-thread is cut on its point, on which a nut is screwed. J J are vertical spikes with hooking-heads. These spikes are passed down through notches in the base of the plates B B, and through holes in the plate E, and their heads are made to overhang a portion of the base of the plates B B, and also of the rail.

The chair jaws or plates B B are to be made of wrought or other suitable metal, and of a thickness sufficient to sustain the weight brought to bear upon the rail. Their form may be either as shown in the sectional drawing Fig. 3, or Fig. 4, as circumstances require.

My chair dispenses with a second tie-bolt at the end where the hinge is constructed, and avoids the inconvenience which would arise from withdrawing this bolt, and from handling the different parts of the chair in the operation of applying the chair to the joint of the rail, and removing the same therefrom.

Having thus described my invention, what I claim as new, and desire to secure by Letters Patent, is—

1. The jaws B B, hinged together beneath the rail at one of their ends, so as to open and

close horizontally, substantially as and for the purpose described.

2. The combination of the jaws, hinged together beneath the rail at one end, and tied together by a bolt at the other end passed under the rail, with the base-plate and vertical spikes, substantially as described.

Witness my hand in the matter of my ap-

plication for patent for improvement in chairs for railroad-rails this 14th day of January, A. D. 1876.

EDWARD RUANE. [L. S.]
